DOUBLE TANK WATER HEATER AND INCINERATOR

Original Filed Feb. 15, 1939

Fig. 1.

UNITED STATES PATENT OFFICE

2,641,231

DOUBLE TANK WATER HEATER AND INCINERATOR

Michael J. Tierney, Rochester, N. Y.

Substituted for abandoned application Serial No. 256,547, February 15, 1939. This application April 21, 1952, Serial No. 283,295

3 Claims. (Cl. 122—2)

1

The invention relates to a double tank water heater and incinerator.

This application is a substitute for application Serial Number 256,547, filed February 15, 1939, now abandoned.

A primary object of the invention is to utilize, in a water heater and incinerator, to better effect the heat ordinarily wasted from a gas water heater; to provide for extracting more heat from the waste gases by extending the heat travel thereof without any attendant precipitation or condensation of the burnt gases, whereby the burnt gases may be effectively used for the heating of water and a considerable saving in the consumption of fuel is effected.

Another object of the invention is to provide a double tank water heater and incinerator adapted to effect a considerable saving in the consumption of gas whether or not refuse is burned and with no attendant precipitation or condensation of the burnt gas.

Another object of the invention is to provide a combination water heater and incinerator having a lower primary burner heated storage tank and an upper secondary tank heated by waste gases passing from the burner of the primary storage tank through an incinerator and its ash pit without any precipitation or condensation within the ash pit or incinerator chamber, whereby the burnt gases may be effectively used for heating water in the secondary tank prior to the passage of the burnt gases to the chimney or flue to which the water heater and incinerator may be connected.

A further object of the invention is to provide a double tank water heater and incinerator in which a gas is burned for heating water in a primary storage tank and the burnt gas subsequently utilized for drying garbage and other refuse thereby eliminating the odors incident to the burning of wet garbage.

Still another object of the invention is to provide a double tank water heater and incinerator having a lower burner heated storage tank and an upper secondary tank and provided between the tanks with an incinerator comprising an upper combustion chamber and a lower ash pit, whereby the burnt gases may be caused to travel upwardly from a burner at the bottom of the primary storage tank and pass around the ash pit and through the combustion chamber of the incinerator for drying refuse therein and finally pass upwardly through the secondary tank for heating water therein prior to the discharge of the burnt gases into a chimney or flue whereby a maximum amount of heat is extracted from the

2

burnt gases and dry refuse may be burned in the incinerator to supplement the action of the burnt gases in heating the water within the secondary tank.

5 With these and other objects in view, the invention consists in the construction and novel combination and arrangement of parts herein-after fully described, illustrated in the accompanying drawings and pointed out in the claims 10 hereto appended, it being understood that various changes in the form, proportion and minor details of construction, within the scope of the claims, may be resorted to without departing from the spirit or sacrificing any of the advantages 15 of the invention.

In the drawings:

Fig. 1 is an elevation of a double tank water heater and incinerator constructed in accordance with this invention.

20 Fig. 2 is a vertical sectional view of the same on an enlarged scale, taken substantially on the line 2—2 of Fig. 1.

Fig. 3 is a horizontal sectional view taken substantially on the line 3—3 of Fig. 2.

25 Fig. 4 is a horizontal sectional view taken substantially on the line 4—4 of Fig. 2.

In the accompanying drawings in which is illustrated the preferred embodiment of the invention the double tank water heater and incinerator 30 comprises in its construction an outer casing 1 constructed of galvanized sheet metal or other suitable material and preferably of cylindrical form but the double tank water heater and incinerator may be of any other desired form. The casing 1 which is provided with a horizontal top wall 2 is also preferably provided with an insulating lining 3 of mineral wool or other suitable material which extends around an inner cylindrical shell 1^a. The top wall 2 of the outer casing 1 is preferably in the form of a cap and is provided 35 with a peripheral flange 4 which is fitted on the upper end of the cylindrical body portion 1 of the casing but the cap or top wall may be secured to the body portion of the casing in any other desired manner.

40 Within the lower portion of the inner shell 1^a is arranged a primary storage tank 5 designed to be constructed of galvanized sheet metal or other suitable material and provided with an upwardly 45 inset concavo-convex bottom wall 6 which forms a dome shaped structure for directing burnt gases from a lower burner 7 into a vertical flue 8. The vertical flue 8 extends entirely through the lower primary storage tank and is provided with a baffle 50 9 preferably of spiral form for causing the burnt

gases to pursue a circuitous course in passing through the flue. The top wall 10 of the primary storage tank is also preferably of concavo-convex form and the burnt gases issuing from the upper end of the flue 8 pass upwardly in the inner shell 1^a around an ash pit 11 and inwardly over the top of the same and through a grate 12 into the incinerator combustion chamber 13.

The burner 7 may be of any desired construction and the gas supply pipe 14 is provided with a gas valve 15 and is also equipped with a pilot light assembly 16 of standard construction and a thermostat 17 also of standard construction controls the feeding of gas to the burner. As these features are of the ordinary construction and do not constitute a portion of the present invention further description thereof is deemed unnecessary. Leading off from the top of the primary storage tank 5 to the house service line is a hot water supply pipe 18. Connected with the pipe 18 is a safety valve or blow-off 19 which operates automatically as a relief should the temperature in the tank 5 become too high. A drain pipe 19 for the tank 5 is located at the bottom of the tank and is equipped with a control valve 41.

The ash pit which is designed to be constructed of suitable sheet metal is closed at the sides and bottom and is within, and spaced from, the inner shell 1^a to provide vertical passages 20 to permit the burnt gases to pass upward around the ash pit and over the top thereof into the incinerator combustion chamber 13 as indicated by the arrows in Fig. 2 of the drawings. The ash pit is bolted to the inner shell 1^a but any other suitable means may be employed for mounting or securing the ash pit in the relation stated within said shell. The casing 1 is provided at the front with a door 21 of cast iron or other suitable material covering aligned openings through the casing and inner shell to afford access to the ash pit for the removal of ashes therefrom. Also the casing and inner shell are provided at the back with screened openings 22 opposite the space 23 between the ash pit and the top of the primary or storage tank, and opening to the outside of the casing to furnish draft to the combustion chamber and to permit escape of burned gases should there be any stoppage of the flue leading to the chimney.

The incinerator combustion chamber is provided with a corrugated fire-pot lining 24 of galvanized sheet metal or other suitable material preferably composed of separable sections 25 and hung detachably on hooks 26 mounted on the inner shell 1^a and forming rigid supports for the sections of the fire pot lining of the incinerator combustion chamber. The detachable connection between the sections of the fire pot lining 24 and the shell 1^a will enable any section of the fire pot lining when burnt out to be readily removed and replaced by a new section. The casing and shell are provided at the front with a fire pot door 27 of cast iron or other suitable material covering openings therein which afford access to the incinerator or combustion chamber to enable garbage and other refuse to be inserted in the incinerator for drying and subsequent burning.

The incinerator chamber which is open at the top is arranged in the shell 1^a in spaced relation below an upper secondary tank 28 adapted to supply preheated water to the primary storage tank 5 and designed to be constructed of hot dipped galvanized sheet metal or other suitable material. The upper secondary tank 28 which is of cylindrical form to conform to the configuration of the casing 1 is preferably provided with concavo-

convex top and bottom walls 29 and 30 and a vertical flue 31 extends entirely through the tank 28 and also through the top wall of the casing 1. The extended upper end 32 of the flue 31 is arranged exteriorly of the casing 1 and forms convenient means for the connection of a smoke pipe, not shown, for connecting the double tank water heater and incinerator with a chimney or flue for conducting the burnt gases to the outside atmosphere.

A baffle 33 is located in the space 34 between the incinerator and the upper secondary tank 28 and preferably consists of a horizontal disk of greater diameter than the lower end of the vertical flue 31 and is detachably hung from the bottom 30 of the tank 28 by means of hooks 35 and loops or links 36 but any other suitable means may be employed for mounting the baffle 33. The baffle 33 is adapted to cause the burnt gases and other products of combustion from the burner 7 and also from dry refuse burned in the incinerator, to be deflected horizontally or laterally and to pass around the baffle into intimate contact with the bottom of the secondary tank 28 and the walls of the flue 31 for extracting a maximum amount of the heat remaining in the burnt gases and a maximum amount of heat from the products of combustion resulting from burning refuse within the incinerator.

Cold water is supplied to the secondary tank 28 by a cold water intake pipe 37 that is connected with the city water supply system, said pipe extending through the top of the casing and through the top of the tank 28 and depending from the top 29 of said tank 28 and terminating adjacent the bottom wall of the tank 28. The preheated water contained within the tank 28 is taken from the upper portion thereof by means of a pipe 38 and is delivered to the primary storage tank at a point adjacent the bottom thereof preferably through the drain pipe 19, the latter serving the dual purpose of a drain pipe and an inlet connection for the lower end of the pipe 38 with the interior of the tank 5. The pipe or tube 38 is preferably constructed of copper but may of course be made of any other suitable material. A drain or draw-off valve 39 is provided at the bottom of the secondary tank for drawing off the water thereof when desired and any suitable valve, not shown, may be provided for controlling the flow of cold water through the pipe 37 into the secondary tank.

The improved water heater and incinerator hereinbefore described has been found by actual test to be highly advantageous in operation. Without the burning of refuse in the incinerator chamber, the water in the secondary tank was heated to a substantial extent by the vent gases from the primary tank and there was no condensation of the burnt gases in the chamber between the tanks.

It appears that releasing the vent gases from the relatively small diameter vent flue of the primary tank into a comparatively large and comparatively warm chamber, obviates the condensation which results whenever it is attempted to extract more heat from the burnt gases by extending the heat travel in any heating apparatus beyond a certain point. When refuse was burned in the incinerator, this resulted in a further rise in temperature in the secondary tank.

What is claimed is:

1. A double tank water heater and incinerator including a casing, a lower storage tank located within the casing for the primary heating of

water, a secondary heating tank located within the casing above the primary storage tank and spaced therefrom to provide a comparatively large intervening space between the tanks, an ash pit located within the intervening space and arranged above the primary storage tank and spaced from the casing to provide passages for causing burnt gases to pass across the bottom of the ash pit and up the sides thereof and over the top of the same, an incinerator chamber arranged over the ash pit in spaced relation with the same and of a diameter substantially equal to the interior of the casing and having an open grate for causing the burnt gases to pass through the incinerator chamber for drying refuse, a burner located beneath the primary storage tank, and a flue of comparatively small diameter extending upwardly through the primary storage tank from the bottom to the top thereof for passing burnt gases from the burner through the storage tank and for causing the burnt gases to pass around the ash pit and through the incinerator chamber and expand before contacting with the secondary tank, the expansion of the burnt gases preventing condensation and precipitation of moisture and extending the heating range of burnt gases and enabling an increased amount of heat to be extracted from burnt gases.

2. A double tank water heater and incinerator including a casing, a lower primary storage tank located within the casing, a secondary heating tank arranged within the casing above the primary storage tank and spaced therefrom to provide a comparatively large intervening space between the tanks, an ash pit located within the intervening space above and spaced from the primary storage tank and having a space there-around to provide passages for causing burnt gases to pass across the bottom of the ash pit and up the sides thereof and over the top of the same, an incinerator chamber arranged over the ash pit in spaced relation with the same and of a diameter substantially equal to the interior of the casing and having an open grate for causing the burnt gases to pass through the incinerator chamber for drying refuse, a burner located beneath the primary storage tank, and a flue of comparatively small diameter extending

upwardly through the primary storage tank from the bottom to the top thereof for passing burnt gases from the burner through the primary storage tank and for causing the burnt gases to pass around the ash pit and through the incinerator chamber and expand before contacting with the secondary heating tank, said casing being provided at the intervening space between the tanks with an opening communicating with the outside atmosphere for furnishing draft to the incinerator chamber and for permitting the escape of burnt gases should the means for connecting the water heater and incinerator with the chimney become clogged.

15 3. A double tank water heater and incinerator including a casing, a lower storage tank located within the casing for the primary heating of water, a secondary heating tank located within the casing above the primary storage tank and spaced therefrom to provide a comparatively large intervening space between the tanks, an incinerator chamber located in said space and spaced from the secondary tank and comprising a horizontal grate and walls extending upwardly

20 25 30 35 40

from the grate and having a door for the introduction of refuse into the incinerator chamber, said grate providing passages for burnt gases, a burner located beneath the primary storage tank and a flue of comparatively small diameter extending upwardly through the primary storage tank from the bottom to the top thereof for passing burnt gases from the burner through the storage tank and for causing the burnt gases to pass through the incinerator and expand before contacting with the secondary tank, the expansion of the burnt gases preventing condensation and precipitation of moisture and extending the heating range of burnt gases and enabling an increased amount of heat to be extracted from the burnt gases.
